UNITED STATES PATENT OFFICE.

JOHN W. DAVIES, OF READING, MASSACHUSETTS.

EMULSIFIER AND CLARIFIER.

1,279,287.

Specification of Letters Patent. Patented Sept. 17, 1918.

Application filed April 23, 1917. Serial No. 163,966.

To all whom it may concern:

Be it known that I, JOHN W. DAVIES, a citizen of the United States, residing at Reading, in the county of Middlesex and State of Massachusetts, have invented an Improved Emulsifier and Clarifier, of which the following is a specification, reference being had to the accompanying drawings, forming part thereof.

10 This invention has reference to improvements in machines for emulsifying milk and other liquid or semi-liquid material, which machine is also adapted to clarify such material or other more or less solid material having or composed of constituents some of which differ as to specific gravity from others.

One object of the invention is to provide 20 an emulsifier adapted to be economically driven in which the material to be treated, under pressure produced by centrifugal action, may be forced between novel squeezing elements carried by the container in which said centrifugal action is produced.

25 Another object of the invention is to provide a machine of this nature having a rotary container furnished with a series of restricted outlets so constructed that a considerable body or quantity of comparatively 30 heavy material can, under centrifugal action, be retained in said container while other material of comparatively lighter weight can be forced by centrifugal pressure through said outlets.

35 Another object of the invention is to improve the construction of the emulsifier devices.

Other objects of the invention will appear from the following description.

40 The invention consists in the rotary container having the novel outlet units.

The invention also consists in such other novel features of construction and combination of parts as shall hereinafter be more 45 fully described and pointed out in the claims.

Figure 1, represents a vertical sectional view of parts of the improved emulsifier and clarifier.

Fig. 2, represents a horizontal sectional view taken on line 2 Fig. 1, on a scale larger than Fig. 1.

Fig. 3, represents a sectional view taken on line 3—3 Fig. 2.

In carrying this invention into practice I 55 construct a machine having the base 5 hav-

ing at its upper end the head 6 furnished with a suitable bearing 7. The wall of the base 5 is furnished with the gear case 8 having the casing member 9 for the worm shaft 10 which is rotatably mounted in the 60 bearings 11 and 12 of said casing member 9 and is sustained by the step bearing 13. This worm shaft 10 is driven by the worm gear 14 which is inclosed by the casing 8 and is operated at a suitable speed in any well 65 known manner.

Removably coupled to the worm shaft 10 is the upper shaft member 15 which is journaled in the bearing 7 of frame head. Mounted on this shaft member 15 is the 70 container or receptacle 16 for the liquid or material to be treated. This receptacle 16 has the flat bottom 17, the annular wall 18 and the inwardly extending guard or apron, 19, open at its central portion as shown in 75 Fig. 1. Preferably but not necessarily this receptacle 16 is made of cast metal, its wall 18 and apron 19 being integral with its bottom 17 and the latter is flat and unobstructed to facilitate the centrifugal 80 action, of material supplied thereto, under rotation of said receptacle.

Wall 18 of receptacle 16 has a series of openings in each of which is mounted a radially and inwardly extending outlet or 85 emulsifier unit comprising the casing 20 having the head 21 furnished with the perforations 22, 22 and the deflector 23 spaced from said head 21, toward the axis of receptacle 16, and extending laterally beyond the 90 perforations 22, 22 to prevent direct flowage of liquid to such perforations. The inner wall of casing 20 is screw threaded to receive the screw threaded emulsifier element or flow controller valve 24 which has the 95 axial perforation 25 having the flaring inner end 26 which is embraced by the annular bearing member 27 and by the annular clearance 28.

Bearing member 27 is, by the screwing 100 of element 24 into casing 20, adapted to be adjusted to bear against or approximately against the co-operating surface of head 21, the clearance or channel 28 of this plug element 24 being in registry with the perforations 22, 22 so that material under pressure passing through said perforations 22, 22 will be received by said clearance 28 and will or may then pass between the annular bearing or emulsifier member 27 and the 110

wall of head 21, the action of passing the material between these parts depending somewhat upon the adjustment of plug element 24. Ordinarily these parts will be so adjusted that the fat globules of milk passing therebetween will be disrupted.

Mounted on the head 6 is the pan 29 having the downwardly inclined wall 30 furnished with the annular wall 31 having 5 the outlet 32. Into wall 31 is received the similar wall 33 of cover member 34 which has the flaring deflector 35 and the top 36 carrying the chamber 37 which is adapted to receive liquid to be treated and has the 10 axially disposed inlet pipe 38 which is slid- able in a bearing of said chamber 37, and extends through the opening in the guard 19 of receptacle 16 and is adapted to deliver material to be treated adjacent the bottom 15 20 25 30 35 40 45 50 55 60 65 70 75 80 85 90 95 100 105 110 115 120 125 130

In making use of this machine as an emulsifier the plugs 24, are suitably adjusted in their casings 20, the receptacle 16 is caused to rotate at the desired speed and 25 milk or other liquid to be treated is placed in the chamber 37 and passes through pipe 38 into said receptacle 16. Under centrifugal action caused by rotation of said receptacle the milk or liquid becomes banked 30 against the annular wall 18 and the heavier particles of foreign matter are driven toward said wall 18 and adhere to the film or layer of milk or liquid covering said wall. As soon as the body of milk or liquid adjacent the wall 18 becomes large enough 35 to cover the inwardly extending casings 20, and the pressure generated in said milk or liquid by centrifugal action is sufficient the milk or liquid will be forced through the 40 perforations 22, of casings 20, into the clearances 28, of the plugs 24, and thence between the elements 27, of said plugs and the coöoperating wall of head 21 and in such passage a large proportion of the globules 45 or particles of such milk or liquid will be broken up or disrupted. The emulsion thus made will then pass through the perforations 25, of the plugs 24, and will be delivered into pan 29.

50 The deflectors 23, prevent the direct passage of the liquid in receptacle 16 to the outlets or perforations 22, so that such liquid reaches said outlets indirectly after the foreign matter has had an opportunity 55 to pass toward the wall 18 and at a time when the liquid is under considerable pressure.

The extension of the outlet units, comprising casings 20, inward from the wall 18 60 has the advantage that a large body of impurities, foreign matter, or matter of any kind and of suitable specific gravity may accumulate and be retained at or near said wall 18 without obstructing the perforations 65 22. This is particularly desirable when the

machine is used to clarify a material of the nature of cocoa in which it is desired to retain the heavier cocoa constituents within the receptacle 16 and to drive off the lighter oily constituents. In this case the crude 70 cocoa is supplied to receptacle 16 and, by its rotation, is placed under centrifugal action whereupon the heavier constituents are forced toward the wall 18 more rapidly than are the lighter constituents with the 75 result that the former accumulate at the wall 18 while the latter may pass outward through the perforations 22, 22.

Having thus described my invention I claim as new and desire to secure by Letters Patent—

1. An emulsifier or similar machine comprising a rotary receptacle having a cylindrical liquid confining wall and one or more outlet units extending inward from said wall 85 whereby the outlet passages of said units are spaced from said wall.

2. An emulsifier or similar machine comprising a rotary receptacle having a cylindrical wall and one or more outlet units extending inward from said wall, said units having outlet passages and deflector means to intercept material passing toward said 90 passages in one direction.

3. An emulsifier or similar machine comprising a rotary receptacle having a cylindrical liquid confining wall and one or more outlet units extending inward from said wall, said units having outlets at their inner 95 ends.

4. An emulsifier or similar machine comprising a rotary receptacle having a cylindrical wall and one or more outlet units extending inward from said wall, said units having outlets at their inner ends and a deflector spaced from said outlets.

5. An emulsifier or similar machine comprising a rotary receptacle having a cylindrical liquid confining wall and one or more outlet units projecting inward from said 110 wall, each of said units having an emulsifier element.

6. An emulsifier or similar machine comprising a rotary receptacle having a cylindrical liquid confining wall and one or more outlet units projecting inward from said wall, each of said units having means to resist the passage of liquid to a point to effect disruption of globules contained in said liquid.

7. An emulsifier or similar machine comprising a rotary receptacle having a cylindrical wall and one or more outlet units extending inward from said wall, each of said units having a pair of squeezing elements of 115 which one is adjustable.

8. An emulsifier or similar machine comprising a rotary receptacle having a cylindrical wall and one or more outlet units extending inward from said wall, each of said 120 125 130

units having a pair of squeezing elements of which one has a clearance communicating with the outlet passages of said unit.

9. An emulsifier or similar machine comprising a rotary cylindrical receptacle having in its wall one or more outlet units each constituted by two elements of which one is adjustable relative to the other, which elements are adapted to coöperate to exert an emulsifying action on liquid passing therebetween under pressure.

10. An emulsifier comprising a rotary receptacle having one or more outlets traveling with said receptacle and means adjustable 15 within and coöperating with each outlet to resist the flow of liquid under pressure gen-

erated by rotation of said receptacle to exert an emulsifying action on said liquid.

11. An emulsifier comprising a rotary receptacle having one or more outlet units extending radially thereinto and having at their inner ends perforations and deflector means.

12. An emulsifier comprising a rotary receptacle having one or more outlet units 20 extending radially thereinto and having outlet passages, and a plug adjustable in each of said units and having a squeezing element adapted to coöperate with another element to constitute a restricted passage.

JOHN W. DAVIES.
